(57) **CLAIM**

The ornamental design for a tender chock, as shown and described.

DESCRIPTION

FIG. 1 is a first perspective view of a tender chock; FIG. 2 is a second perspective view of the tender chock shown in FIG. 1;

FIG. 3 is a third perspective view of the tender chock shown in FIG. 1;

FIG. 4 is a front view of the tender chock shown in FIG. 1;

FIG. 5 is a back view of the tender chock shown in FIG. 1;

FIG. 6 is a left side view of the tender chock shown in FIG. 1;

FIG. 7 is a right side view of the tender chock shown in FIG. 1;

FIG. 8 is a top view of the tender chock shown in FIG. 1; and,

FIG. 9 is a bottom view of the tender chock shown in FIG. 1.

The dashed lines in FIGS. 1-9 are included for the purpose of illustrating portions of the tender chock that form no part of the claimed design.
